UNITED STATES PATENT OFFICE.

WILLIAM J. WRIGHT, OF BALTIMORE, MARYLAND.

BOOK-IDENTIFICATION DEVICE.

Application filed January 17, 1928. Serial No. 247,448.

This invention pertains to identification devices and more particularly to devices of such character which are adapted to be secured to books or paper binders.

5 In certain industries, such as those which supply gas and electricity to the public, a number of men are employed whose duty it is to go to the different houses which use gas and electricity in a certain section or route and 10 read the meters therein, making notations of such meter readings in a route book, said route book usually consisting of a binder having secured therein a number of loose leaves. Upon the back edges of these leaves it has been cus- 15 tomary to apply, as by stenciling, an identification numeral.

Due to continual and rough handling by the meter reader and the practice of removing and changing some of the leaves in the binder, the identification number on the back 20 edges of the leaves frequently becomes damaged to such an extent that it is difficult and sometimes impossible to read the identification number thereon.

25 An object of this invention is to provide an identification device for books and binders of the aforementioned character which may be expeditiously and securely mounted on said book or binders and which will be practically 30 indestructable when in use.

A further object of the invention is the provision of a device of this character which will be simple in construction, efficient in operation and which may be manufactured at 35 low cost.

Other objects of the invention will be apparent from a study of the following specification taken in connection with the accompanying drawings, wherein:

40 Figure 1 is a side elevation of a binder having secured therein a plurality of sheets of paper and showing my device secured on the rear end thereof.

Figure 2 is an end view of the binder showing 45 my device in elevation.

Figure 3 is a view taken centrally through the binder showing the manner of securing my device thereon.

Figure 4 is a side view of my device partly 50 in section and detached from the binder.

Figure 5 is a fragmentary view partly in section showing one end of the invention.

The reference character 1 indicates a conventional binder having secured therein, by 55 suitable means such as cross strips 2, a plurality of paper sheets 3.

My invention comprises an elongated strip 4 of any suitable material, such as metal, having extending therefrom at its opposite ends and at right angles thereto, a pair of lugs 5 of equal length. On the side opposite lug 5 the strip 4 is also provided with an identification number 4'. Lugs 5 are provided at a point remote from metal strip 4 with tapered openings 6 and 7.

A bar or rod 8, of less length than strip 4, and having on one end thereof an enlargement 9 terminating in a tapering head 10, is adapted to be passed through the opening 6, the enlargement 9 serving as a guide for head 10. 70 The tapered sides of head 10 are adapted to engage the tapered walls of opening 6, thus acting as a stop to limit the inward movement of rod 8 therethrough. When in this position, the outer face of head 10 is flush with the 75 outer side of lug 5.

The opposite end of rod 8 is provided with an enlargement 11 terminating in threaded portion 12. A fastening device 13 serves to secure the free end of rod 8 to the adjacent 80 lug 5, said fastening device comprising a shank having a bore extending therethrough from one end to a point near the opposite end. At a point remote from the open end thereof, bore 14 is provided with a beveled shoulder 15 terminating in a reduced threaded portion 16 and adapted to receive the threaded end of bar 8 therein. The outer end of fastening device 13 is provided with a head 17 having tapered side walls adapted to engage 85 the walls of opening 7 in which position the outer face of said head is flush with the outer face of lug 5. Tapered head 17 is also provided on the outer face thereof, with a groove 90 for the purpose of receiving a suitable actuating tool such as a screw driver.

The operation of my device is as follows:

When applied to a binder of the type illustrated in the accompanying drawings, securing element 13 is detached from rod 8 and said 100 securing device and rod are withdrawn from their respective openings in lugs 5. Strip 4 is then positioned against the back edges of the sheets in said binder, the lugs 5 thereon extending forwardly over a portion of the upper and lower side edges of said sheets. The binder and sheets therein are then opened and rod 8 is passed through opening 6 in lug 5, and projected past the securing strips 2 of binder 1 adjacent that side of said strips 2 105 opposite strip 4. Securing element 13 is then passed through opening 7 in lug 5, the larger 110

portion 14 of the bore therein passing over threaded end 12 of bar 8 and together with beveled shoulder 15, serving as a guide to position said threaded end in alignment with 5 the threaded portion 16 of the bore. A suitable tool is then placed in the groove in head 17 by means of which securing element 13 is screwed onto rod 8 until heads 10 and 17 have been drawn into and lie flush with lugs 5.

10 In this position, the accidental displacement of the device is prevented by the cross strips 2 of the binder.

What I claim is:—

1. A device of the character described comprising an elongated metal strip, identification data carried on one side of said strip, transversely extending perforated lugs of equal length on the opposite side of said strip and at the opposite ends thereof, means carried by said lugs for securing the strip on a binder, said means comprising a rod adapted to be passed through the perforation in one of the lugs, a tapered head carried on one end of the rod and adapted to engage the walls of 20 said perforation, a guide portion intermediate said head and rod for directing the head into the perforation, threads carried by the 25

opposite end of the rod, and a securing element extending through the perforations in the other of the lugs for engagement with the threaded end of the rod. 30

2. A device of the character described comprising a metal strip provided at its opposite ends with transversely extending perforated lugs, a securing rod carried by one of said lugs, and means carried by the other of said lugs adapted for threaded engagement with one end of said rod for supporting same, said means comprising a headed shank having a bore therein open at one end, that portion of the bore adjacent the open end thereof being of greater diameter than the rod, a beveled shoulder in said bore and at a point remote from the open end thereof and together with the aforementioned bore portion constituting a guide for the rod and a threaded portion of less diameter than the rest of the bore adapted to receive the threaded end of the rod after the same has been brought into alignment therewith by the guide. 40 45 50

In testimony whereof, I affix my signature hereto.

WILLIAM J. WRIGHT.
